(57) **CLAIM**

The ornamental design for a toilet plunger head, as shown and described.

DESCRIPTION

FIG. 1 is a side elevation view of the toilet plunger head in context of an assembled toilet plunger;

FIG. 2 is a front perspective view of the toilet plunger head;
FIG. 3 is a top plan view of the toilet plunger head of FIG. 1;

FIG. 4 is a bottom plan view of the toilet plunger head of FIG. 1;

FIG. 5 is a rear end plan view of the toilet plunger head of FIG. 1;

FIG. 6 is a front end plan view of the toilet plunger head of FIG. 1;

FIG. 7 is a left side view of the toilet plunger head of FIG. 1; and,

FIG. 8 is a right side view of the toilet plunger head of FIG. 1.

The design consists of the features of shape, configuration, pattern, and ornamentation of the toilet plunger head or a combination of any of these features, as shown in the drawings. The portions shown with dashed lines do not form part of the design and are included for the purpose of illustrating non-design portions of the article that are part of the article but not part of the design.
